Application April 4, 1955, Serial No. 498,843

5 Claims. (Cl. 131—108)

This invention relates to the processing of tobacco, and especially to the sequence of steps involved in the treatment and handling of tobacco to produce cigarettes. It is concerned with improvement in operations performed upon the tobacco strips between the time they are removed from the hogsheads or bales in which they are aged, and completion of the finished cigarette.

While details of operation differ in different plants, in a characteristic cigarette manufacturing operation tobacco strips from the bales or hogsheads are first blended to produce a composite blend of each individual type, by manual deposit of the strips from separate hogsheads or bales in overlapping relationship on a travelling conveyor belt. The resulting composite blends are in turn blended with each other by similar laminated deposit on a further conveyor belt, and the resulting blended product is softened by steaming, sprayed with casing fluid and then bulked by storing in large piles for substantial lengths of time to accomplish distribution of moisture and flavoring constituents. It is then cut to the desired particle size, dried, cooled and again bulked for a period which may vary between three hours and four days. It may also be redressed by a tumbling operation, before being fed to the individual machines for manufacture into cigarettes. In addition to these steps, the process includes special dipping and drying steps applied to Burley tobacco and a sand screening step to Bright tobacco.

While these operations are admirably adapted to attainment of the finished product insofar as basic principle is concerned, they leave much to be desired in the way of uniform control and saving of labor and space. For example, the blending as performed by manual deposit of tobacco on a travelling belt from a number of sources by a number of operators is at best, crude and unreliable, and cannot be corrected in subsequent stages of manufacture, when it has been carelessly or inaccurately done. Any attempt to correct by later blending an error committed at this time is a resort to blind chance.

Furthermore, while certain details and sequences of operation have been performed by continuous operation upon the tobacco in transit, the process has been interrupted at bulking steps for storage of the tobacco for considerable periods of time, and this has created expense on account of both the space and labor utilized. It has also introduced a further erratic factor into the operation by reason of the variable time factor involved in bulking in this manner, and has rendered the scientific control of material in the plant very difficult.

It has heretofore been proposed to provide a process which is continuous, starting with the individual leaves before stemming, but such a process is prohibitive, both because of the labor required and because of the space and equipment requirements. It does not admit of the incorporation of the highly desirable dipped filler Burley tobacco and does not provide for bulking, in the way required in the modern industry.

The necessity for providing prolonged bulking to produce a satisfactory end product has imposed a hitherto

2

insuperable obstacle to the development of a commercially satisfactory process in which the flow of tobacco is maintained continuously under close control, from the strips in the bale or hogshead to the finished cigarette.

5 The achievement of this end has been the primary object of this invention.

A further object of the invention has been to provide a process in which the control of the proportions of tobaccos blended and of the amount of time involved in 10 each successive step, especially the bulking, is accurately predetermined and maintained.

A further object has been to provide a process in which the flow of materials may be maintained continuously but in which certain operations are performed in alternate step-wise progression in parallel lines of the system, where prolongation of time is necessary in a particular part of the processing.

Still further objects and advantages of the invention, and the manner in which they have been attained, will be 20 evident from reading of the following detailed description in the light of the attached drawing, in which,

Figure 1 is a flow sheet, illustrating in diagrammatic form the steps of handling the tobacco from its removal from the hogshead or bale to its delivery in the form of 25 packaged cigarettes,

Figure 2 is a partly diagrammatic plan view of the apparatus for performing the blending, preliminary treatment and casing steps,

Figure 3 is a similar view of the strip bulking, ordering, cutting, drying and cooling steps,

Figure 4 is a similar view of the cut tobacco bulking, cigarette making and packaging steps,

Figure 5 is a cross section on the line 5—5 of Figure 2, illustrating the preliminary blending steps,

Figure 6 is a cross section on the line 6—6 of Figure 2, illustrating the steaming, dipping and drying steps, as performed upon the blended Burley tobacco,

Figure 7 is a cross section on the line 7—7 of Figure 2, illustrating the steps of screening and steaming as performed upon the Bright tobacco,

Figure 8 is an end view of the conveyor system illustrated at the bottom of Figure 2.

Figure 9 is a cross section on the line 9—9 of Figure 3, illustrating the strip bulking, ordering, cutting, drying and cooling steps,

Figure 10 is a cross section on the line 10—10 of Figure 3 illustrating the feeding system by which tobacco is fed alternately to the strip bulking lines arranged in parallel in the system,

Figure 11 is a cross section on the line 11—11 of Figure 4, illustrating the cut tobacco bulking, cigarette making and packing steps, and

Figure 12 is a cross section on the line 12—12 of Figure 4.

55 For convenience in understanding the invention, the processing steps will first be described in brief outline in relation to the flow sheet of Figure 1 of the drawing and thereafter discussed in greater detail in relation to the other figures.

The various types of tobacco, such as Bright at 15, Burley at 16, Maryland at 17 and Turkish at 18, are delivered in strip form from their respective aging units such as hogsheads or bales to automatic feed mechanisms 19, 20, 22 and 23, respectively, by which they are fed to blending apparatus 24, 25, 26 and 27, in which leaves of each type are blended with other grades of leaves of that type to obtain a representative composite from a number of bales or hogsheads. A special system of alternate operations is performed in blending lines arranged in parallel, as discussed hereinafter.

70 The blended composite strip stock is fed continuously by one or the other members of pairs of automatic feed

devices 28, 29, 30, 32, so that tobacco is discharged continuously from each of the respective blending systems. The tobacco of each type is then subjected, during further continuous transit, to treatment appropriate to its own type, the Bright passing through sand screen 33 and steam cylinder 34, the Burley through steam cylinder 35, automatic feed 36, dipping tank 37, automatic feed 38 and dryer 39, and the Maryland and Turkish through steam cylinders 40 and 42, respectively, before the four types are combined by passage upon their respective automatic feed conveyors 43, 44, 45 and 46 to a conveyor 47 on which they are laminally deposited to produce a blend of all four types.

From conveyor 47, the laminated composite product is passed by automatic feed conveyors 48 to casing cylinders 49, in parallel lines as illustrated, and thence by conveyor 50, to a system of conveyors 51 by which it is passed in stepped progression to and through parallel bulking apparatus 52. From this bulking apparatus, it passes on through automatic feeding apparatus at 53, ordering at 54, cutting at 55, drying at 56 and cooling at 57. The cutting is in turn performed in separate parallel lines, as illustrated in Figures 1, 3 and 9.

The cut, dried and cooled tobacco is next passed by conveyor 58, to a system of conveyors 59, and from these conveyors it is passed in stepped progression through parallel bulking apparatus 60 to conveyor 62. From conveyor 62 it is passed by conveyors 63 and 64 to a system of conveyors 65 by which it is passed to the hoppers 66 of automatic feed devices 67 which provide a constant supply for each of the cigarette making machines.

The tobacco is passed continuously from hoppers 66 by automatic feed conveyors 67 to a system of conveyors 68, by which each of the hoppers of cigarette making machines 69 is fed intermittently at a rate sufficient to maintain a supply at each machine to enable it to be run continuously. From the individual cigarette machines (nine as illustrated in Figures 1, 4 and 12), the finished cigarettes are passed to associated packaging machines 70, as is conventional in the art.

As discussed above, the process and system of the invention provide important advantages in saving of labor, consistent high quality of the resulting product and economy in use of space and equipment. They also provide a considerable degree of flexibility in operation, but before discussing this aspect it will be best for us to consider the more detailed aspects of the process as applied in uniformly controlled operation utilizing an established sequence. In such operation, tobacco strips may first be transferred from their respective hogsheads or bales and introduced into the hoppers of the automatic feed devices or conveyors 19-23 by operation of slabbing forks 72, which remove the strips from the upper end of the bale or hogshead while it is supported and intermittently raised from its lower end on an elevator mechanism 73, as illustrated in Figure 5.

As well understood in the art, each of the automatic feed devices 19-23, as well as other devices designated "Auto Feed" in Figure 1, comprises in addition to the hopper 71 an upwardly inclined endless conveyor 74 (see Figure 5) having upstanding pins or the like which form bucket-like spaces between which the tobacco is collected and elevated, and a levelling kicker 75 is rotated in a direction opposed to the upward passage of the tobacco. The conveyors of these automatic feed devices are driven at a controlled constant speed by adjustment of the variable speed drive mechanism through which they are driven, and this together with operation of the kicker, results in delivery of tobacco from conveyor steadily at exactly the rate desired. From the upper end of conveyor 74, the strip tobacco is delivered to a conveyor 76 on which it is fed at a uniform rate to one or the other of a pair of blending units. Since the principle of operation of these units is identical for each of units 24-27,

4
a description of unit 25, as illustrated in Figures 2 and 5, will suffice for all.

As illustrated in broken lines at the top of Figure 2, each of the conveyors 76 is mounted for swinging movement in which it feeds tobacco to one or another of blending units 77 and 78, and in operation conveyor 76 is swung to position in which a quantity of tobacco from a number of bales or hogsheads is fed to blending unit 77 until a complete blended increment is accumulated thereon, and is then swung into the broken line position for similar blending in unit 78. While unit 78 is being loaded with a blend of tobaccos in this manner, tobacco blended in the immediately preceding loading of unit 77 will be fed continuously forwardly and through the other steps of the process, and when unit 78 has been loaded and conveyor 76 swung back into position to load unit 77, tobacco in unit 78 will similarly be fed forwardly. Thus, while the feed to each of units 77 and 78 is intermittent, the delivery of each of the types of tobacco from their respective blenders is continuous, since the paired units alternate between loading and feeding operations.

The detailed operation of the blending units is illustrated in Figure 5. Each such unit may comprise an endless conveyor 79, mounted on rollers or pulleys 80 which are spaced apart about half the length of an underlying endless conveyor 82 which is also mounted within the walls of housing 83 in which conveyor 79 is mounted. The rollers 80 are mounted and driven for rotation in either direction and also for translatory movement between the ends of housing 83, as illustrated in broken lines in Figure 5.

In starting up the apparatus, conveyor 79 may first be mounted at the extreme right of Figure 5 and the rollers 80 rotated in a clockwise direction while tobacco is fed onto this conveyor by conveyor 76. As tobacco progresses to the right on conveyor 79 until it covers the upper run of that conveyor, it will begin to spill over onto conveyor 82 during further feed, and the translatory movement of conveyor 79 toward the opposite end of the housing will then be commenced, with tobacco deposited progressively on conveyor 82 in a uniform layer along the right half of its length as illustrated in Figure 5.

As the conveyor carriage reaches the end of its leftward movement, the rotation of rollers 80 will be reversed, so that the upper run of conveyor 79 will move in the opposite direction, and tobacco will accumulate on this run to the left as it is received from conveyor 76. As soon as this tobacco reaches the left end and begins to spill over, the carriage on which rollers 80 are mounted will start its movement in the opposite direction, and a layer of tobacco will be deposited on the left half of conveyor 82. After repetition of this sequence a number of times during continuous feed of the tobacco onto conveyor 76 from a number of hogsheads or bales, the desired representative composite from these bales will have been deposited on conveyor 82 in successive strata, and conveyor 76 will then be swung into position to repeat this sequence in companion blending unit 78, while the rollers or pulleys 84, which have heretofore been stationary, are rotated clockwise to feed the deposited tobacco to other units of the operation.

From conveyor 82, the Burley tobacco will thus be fed forwardly by conveyor rake 81 and to automatic feed device 29 and thence through the steaming, dipping and drying steps, as heretofore discussed, and the Bright, Maryland and Turkish tobaccos will similarly be subjected to their respective screening and steaming treatments as illustrated in Figure 1, and understood in the art. While pairs of automatic feed devices have been illustrated in Figures 1 and 2 for sequential operation in time with the feed from their associated blending units, it should be understood that the automatic feed from these units may comprise but a single feed device operating

continuously and receiving its supply from the blending units 77 and 78, as these operate alternately to feed the tobacco forwardly.

Each of the automatic feed devices 43, 44, 45 and 46 will be provided with a supply of tobacco in sufficient volume to maintain a continuous feed to the blending belt 47 by the features of the process and system as discussed above, even though slight interruptions may occur in one or more of the operations. As illustrated in Figures 2 and 8, each of these devices deposits tobacco continuously on an associated weighing conveyor 85, 86, 87 or 88, and the tobacco passes forwardly on these weighing conveyors for continuous deposit on blending conveyor 47, to provide laminated deposit of the various types of tobacco on conveyor 47 at the points where the tobacco is received on this conveyor. Each weighing conveyor 85-88 is connected with the variable speed drive control for its associated automatic feed device 43-46, so that the rate of movement of the conveyors of any of these devices is speeded up when its associated weighing conveyor registers less than a predetermined weight and slowed down when the reverse occurs. Tobacco of each type is accordingly fed to conveyor 47 at a uniform rate by weight, regardless of variations in density.

From blending conveyor 47, the laminated blend of tobaccos is fed through automatic feed devices 48 and the casing treatment in cylinders 49, in parallel lines. The purpose of dividing the flow at this point is to provide the desired capacity, and tobacco is delivered by conveyor 89 (Figure 8) to conveyor 90, which is reversed in direction as illustrated by the arrows with sufficient frequency to maintain a supply for continuous feed from both of variable speed devices 48 at all times.

From casing cylinders 49 (Figure 2), the tobacco is fed continuously on conveyors 50 and 92 (Figure 10) to the system of conveyors 51. Assuming that an increment of tobacco is first to be fed to the bulking unit 52 at the extreme left of Figure 10, it passes from conveyor 92 on conveyors 93, 94 and 95, and falls from conveyor 95 onto the top of conveyor 96, whose rollers or pulleys 97 are rotated clockwise to cause rapid movement of the upper run of this conveyor in discharging tobacco into the bin or housing 98 of this unit 52 onto its conveyor belt 99, which is advanced very slowly and steadily during this loading, so as to distribute the tobacco uniformly along its length. The carriage on which the rollers 97 are mounted is also reciprocated slowly as illustrated in full and broken lines in Figure 10, to distribute the tobacco evenly across the width of conveyor 99. As an illustration of comparative speeds which may be used in such a loading operation, conveyor runs of conveyors 96 and 99 may be advanced at rates of the order of 150 feet per minute and 30 feet per hour, respectively, and the carriage on which conveyor 96 is mounted may be reciprocated simultaneously at a rate in the order of 10 feet per minute.

Loading of each of the successive bins 98 is preferably continued until completed, although the invention may also be practiced by loading each bin successively in increments of parts of its length, and unloading each bin from its opposite discharge end as further increments are added after it is fully loaded. Thus, the successive bins from left to right may be loaded in increments of one-third of the length of their respective conveyor belts, and this sequence repeated through three series of operations until completed, with discharge from each bin progressively during the fourth and succeeding loadings in continued operation, or each bin may receive one complete loading in each increment, with continuous discharge from each successive bin during each loading after the first. In either of these cases, the bulking belts 99 will be maintained idle except during loading and unloading in order to obtain full advantage of the capacity of the apparatus.

While the loading and unloading of the bins as discussed above is desirable as an ideal operation to utilize fully the capacity of the apparatus, it has certain practical disadvantages, especially where some part of the operation may temporarily be interrupted or reduced in throughput capacity. To take care of these situations, it is preferable to supply bulking capacity in the bins 98 which is somewhat in excess of that which would suffice for an optimum timed operation as discussed above, and to start the movement of conveyors 99 for feeding of the bulked tobacco forwardly to the other steps of the process after a suitable time interval before the loading of all of the bins has been completed. This is exemplified in Figures 3 and 10, which show five bulking bins to provide excess capacity, as compared to diagrammatic Figure 1, in which only three parallel bulking lines are provided. Thus, for example, the process may well be practiced by a sequence in which the unloading of the endmost bin to the left is commenced after the next two bins have been loaded and the fourth is being loaded, and the unloading of the second may start while the fifth is being loaded, and so on in stepped progression. It should also be noted that the unloading operation may proceed at a slower rate than the loading operation, and that two or more of the bins may be unloaded simultaneously.

Continuing now with discussion of the operations of loading the remaining bulking bins 98, after the bin at the left of Figure 10 has been fully loaded or received a desired increment of loading, a similar load may be delivered to the next bin to the right. To accomplish this, the conveying run movement of conveyor belt 95 is reversed and the rollers 100 supporting belt 102 are rotated in a counter-clockwise direction while the carriage supporting these rollers is reciprocated to distribute the tobacco laterally of the belt 103. The rotation of rollers 100 is next reversed and their carriage is reciprocated through a path to deliver a load of tobacco to the third bin from the left.

The conveyor 94 is next reversed and a similar sequence of steps applied in loading the last two bins from their overlying conveyor 104, the rates of movement of the runs of the conveyors and of translatory reciprocating movement of conveyors 102 and 104 being of the same order as discussed above for loading of the first bin.

From the foregoing discussion it will be evident that one or more of the bulking conveyors will be in process of being loaded at all times once the operation of the system has become established and that one or more of these bulking conveyors will similarly be in process of unloading to provide the necessary continuity of supply to other parts of the system.

The automatic feed devices 53, ordering cylinders 54 and cutters 55, as illustrated in Figures 1, 3 and 9, operate in a manner familiar to those skilled in the art, as do also the drying cylinders 56 and cooling cylinders 57. A continuous supply of tobacco is processed through these steps of the system at all times when the conveyor belts on which the tobacco is bulked are operated to feed tobacco forwardly into their respective automatic feed devices 53. As an alternative to the particular combination illustrated in Figures 1 and 3 of the drawing, in which the parallel lines from the respective bulking bins are maintained separate for performance of these steps, various combinations of cross feed and combination of supply lines from the bulking bins may be provided for combining flow of tobacco from these bins for processing by the cutting machines, or by other apparatus operating in this part of the system.

Regardless of the particular arrangement of the ordering, cutting, drying and feeding steps of the process as discussed above, a substantially continuous supply of tobacco will be maintained to the conveyor 58, and this supply of tobacco will be fed in turn by the system of conveyors 59 (Figure 4), alternately to the respective

cut tobacco bulking units 60. The system of conveyors 59 provides a combination somewhat similar to that employed for feeding the tobacco to the strip tobacco bulking bins, in that it includes a conveyor 105 which underlies the discharge end of the conveyor 58 and overlies, at its discharge end, the receiving end of an underlying conveyor 106. When moved in one direction while receiving tobacco from conveyor 105, the conveying run of conveyor 106 delivers it to a conveyor 107 by which it is fed to the bin 60 at the left in Figure 4, and when the direction of feed of conveyor 106 is reversed, the tobacco will similarly be fed to conveyor 108 by which the center bin 60 is loaded. By reversing the direction of feed of conveyor 105, the conveyor 109 will receive tobacco for loading of the third bin 60.

Each of conveyors 107—109 is oscillated between the broken line positions illustrated in Figure 4 so that the tobacco will be distributed laterally of the conveyors 110 in the bulking bins 60, as it is delivered to these bins, and as it is moved forwardly in these bins by conveyors 110. The same principles discussed above in regard to the bulking bins and conveyors for the strip tobacco are also applicable to the processing of the cut tobacco at this stage, the tobacco being fed alternately into the respective cut tobacco bulking lines in stepwise progression, and also being fed forwardly from these lines in stepwise progression so as to maintain a substantially continuous supply of tobacco fed to conveyor belt 62. The feed of this tobacco by conveyors 62, 63 and 64 to the hoppers 66 of the automatic feeding devices 67 is accomplished in substantially the same manner discussed above in regard to the strip tobacco and cut tobacco bulking feed units, conveyor 112 (Figure 11) serving first to deliver tobacco forwardly on to conveyor 113 while this tobacco is delivered by conveyor 113 to the bin 66 at the left of Figure 11. When this bin has received its desired increment of tobacco, conveyor 113 is reversed and the middle hopper 66 of Figure 11 then receives its increment of tobacco. Conveyor 112 is then reversed to feed an increment of tobacco to the hopper 66 at the right of Figure 11, and the sequence is then repeated, at a sufficient rate and with sufficient frequency in the incremental feeding steps to maintain a desired supply of tobacco in each of the hoppers 66 at all times. Automatic feed devices 67 (Figures 4 and 12) may be operated continuously to supply tobacco from the respective hoppers 66 into the hoppers of each of the respective cigarette making machines 69, which are also continuously supplied in this manner.

Referring to Figure 12 for an illustration of this feed, it will be understood that conveyors 114, 115 and 116 may be used to keep each of the cigarette making machines 69 automatically supplied with sufficient tobacco at all times to maintain their continuous and uniform operation, by utilizing these conveyors 114—116 in exactly the same manner discussed above with regard to conveyors 64, 112 and 113 of Figure 11. Since the operation of the cigarette making machines and packaging machines may be in accordance with principles well established in the art, no detailed description of this part of the operation is necessary.

While the invention has been discussed above in relation to a single illustrated embodiment with certain available modifications and refinements, persons skilled in the art will be aware that it may be modified or refined in a variety of ways within the principles established of maintaining a substantially continuous feed by providing a plurality of locations for blending and bulking, and feeding from certain of these locations while feeding to others.

As examples of available modifications, it should be pointed out that the relative locations and numbers of the units designed for sequential parallel operation may be modified in many ways. The reference to parallel arrangement relates to their functioning in the system

and not to strict geometric parallelism. These units may be arranged in vertically, instead of horizontally, spaced relation and functionally paired units may be separated considerably in location so long as their output passes to a common discharge stream as may be required. The number of associated similar units may also be varied, as for example by providing three or more identical units with alternating timed feed and discharge cycles in place of the pairs of coupled units 77 and 78 for the initial blending.

The variable speed devices used at critical parts of the system introduce advantages both of flexibility of operation and of accurate control. By adjusting the speeds of these devices, a desired change in ratio of tobaccos to be blended may be obtained, and their controlled speed of delivery of tobacco insures accurate proportioning and supply regardless of minor interruptions and fluctuations of the supply of tobacco to these devices.

While the invention relates primarily to the system and its process features, it will be evident that it may advantageously be controlled by timing apparatus and other automation features by which it may be partly or completely mechanized, in any manner available to the engineering profession. Since these and many other features may be adapted in implementation of the invention, it should be understood that the only restrictions to be imposed on its scope are those contained in the following claims:

What is claimed is:

30. 1. In the manufacture of cigarettes, the process comprising feeding strip tobacco from a plurality of aging units each containing tobacco of one type in successive strata to a blending location in a first set of blending locations and thereby establishing a composite blend of that type of tobacco at said location, simultaneously performing similar feeding steps individually upon other types of tobacco at other blending locations in said first set of blending locations to establish separate composite blends of each of said other tobacco types at said other blending locations, then performing similar individual feeding steps of each of said types from said plural aging units at a second different set of blending locations to establish separate bodies of blends of the respective types at said second set of blending locations, feeding the tobacco forwardly from said first set of blending locations during said feeding of tobacco to said second set of locations, thereafter feeding tobacco forwardly from said second set of blending locations while feeding it to said first set of blending locations in repetition of said first set of blending operations, and continuing the sequence of establishing blends of the respective types at one of said locations while feeding forwardly in separate streams the blends established at the other of said locations and establishing a substantially continuous forwardly flowing stream of each of said types of tobacco from said pairs of blending locations, feeding said separately established flowing streams continuously at controlled rates at spaced locations onto a travelling conveyor and thereby establishing a blend of the tobacco of said types, feeding the blend of strip tobacco of said types established on said travelling conveyor continuously forward to a plurality of bulking locations arranged in parallel in stepwise progression, and maintaining at each of said locations the body of tobacco there deposited in depth for a sufficient time period to accomplish the bulking function, feeding forward in stepwise cyclic progression tobacco bulked at said bulking locations and thereby establishing a substantially continuous flow of tobacco to and from said bulking locations, cutting said tobacco continuously during its continued forward feed from said bulking locations, feeding said cut tobacco continuously forwardly to a second set of bulking locations arranged in parallel and there performing bulking and further feeding in stepped progression as defined above for said strip tobacco bulking operations, and feeding the substantially continuous

stream of tobacco received from said cut tobacco bulking operations in stepped progression to a plurality of cigarette making machines at a rate sufficient to maintain a supply at each of said machines during their operation.

2. A process as defined in claim 1 in which tobacco of certain of said types is continuously subjected to screening, steaming and dipping operations during passage from the initial blending operations to the blending operations in which said types are blended with each other.

3. A process as defined in claim 1, in which the blend of types of strip tobacco is continuously cased during passage from the operation of blending of said types to the cyclic stepped parallel strip bulking operations.

4. A process as defined in claim 1 in which said strip bulked and cut tobacco is continuously dried and then cooled during passage from said cutting operation to the cyclic stepped parallel cut tobacco bulking operations.

5. In the manufacture of cigarettes, the process comprising feeding strip tobacco from a plurality of aging units each containing tobacco of one type in successive strata to a blending location in a first set of blending locations and thereby establishing a composite blend of that type of tobacco at said location, simultaneously performing similar feeding steps individually upon other types of tobacco at other blending locations in said first set of blending locations to establish separate composite blends of each of said other tobacco types at said other blending locations, then performing similar individual feeding steps of each of said types from said plural aging

20 25 30

units at a second different set of blending locations to establish separate bodies of blends of the respective types at said second set of blending locations, feeding the tobacco forwardly from said first set of blending locations during said feeding of tobacco to said second set of locations, thereafter feeding tobacco forwardly from said second set of blending locations while feeding it to said first set of blending locations in repetition of said first set of blending operations, and continuing the sequence of establishing blends of the respective types at one of said locations while feeding forwardly in separate streams the blends established at the other of said locations and establishing a substantially continuous forwardly flowing stream of each of said types of tobacco from said pairs of blending locations, and feeding said separately established flowing streams continuously at controlled rates at spaced locations onto a travelling conveyor and thereby establishing a blend of the tobacco of said types.
